(57) **CLAIM**

The ornamental design for a star projection lamp, as shown and described.

DESCRIPTION

FIG. 1 is a perspective view of a star projection lamp showing my new design.

FIG. 2 is a front view of a star projection lamp.

FIG. 3 is a rear view of a star projection lamp.

FIG. 4 is a left side view of a star projection lamp.

FIG. 5 is a right side view of a star projection lamp.

FIG. 6 is a top view of a star projection lamp; and,

FIG. 7 is a bottom view of a star projection lamp.

The broken lines in the drawings depict portions of the star projection lamp that form no part of the claimed design.
